UNITED STATES PATENT OFFICE.

SAMUEL G. STUCKEY, OF LOCKLAND, OHIO, ASSIGNOR TO LEMUEL M. POTTS.

TAPE-MOISTENER.

1,123,816.

Specification of Letters Patent.

Patented Jan. 5, 1915.

Application filed August 11, 1913. Serial No. 784,051.

To all whom it may concern:

Be it known that I, SAMUEL G. STUCKEY, a citizen of the United States of America, and resident of Lockland, county of Hamilton, and State of Ohio, have invented certain new and useful Improvements in Tape-Moisteners, of which the following is a specification.

This invention relates to tape moisteners, in which means are provided for supporting a roll of gummed tape, for moistening the tape and for severing the moistened strip from the roll.

An object of my invention is to produce a tape moistener in which extreme simplicity of construction and economy are obtained.

Another object of my invention is to produce a tape moistener in which the moistening roll, the reservoir and the roll of gummed tape are protected from the drying influences of the air and from dust.

Referring to the drawings, which illustrate a machine embodying my invention, and which form a part of this application, Figure 1 is a plan view of this machine, with the cover removed, showing a roll of tape located therein. Fig. 2 is a sectional elevation, taken on line 2-2 of Fig. 1, and showing the cover in position.

Referring to the drawings: The machine comprises a base 3, forming a receptacle for the roll of tape, a moistening roll 4, and a cover plate or lid 5. The base is provided with an integrally formed annular flange 6, forming a circular receptacle 7, in which a roll of gummed tape 8 is placed. A centering lug 9 is formed upon the base and in the center of the receptacle and about which the roll of tape 8 is adapted to turn. The base is formed with an offset 10, having a circular recess 11, which forms a reservoir for the moistening roll 4. In the center of the reservoir a shouldered journal lug 12 is formed, which rotatably supports the moistening roll. The outer surface 13 of the moistening roll is made of some absorbent material, such as felt, and is extended below the body of the roll

50 to dip into the reservoir, in order that the capillarity of the absorbent material will keep it in a moist condition. One end 14, (see Fig. 1), of the annular flange 6 is brought outwardly where the offset 10 is located and is extended to partially surround the roll 4 and reservoir 11, while the

other end 15 of the flange is brought adjacent to the moistening roll and bent backwardly upon itself, to form a narrow neck, one side of which has a knife edge 16 for 60 severing the moistened strip of tape.

In the upper edge of the flange 6 an annular groove 17 is formed, leaving an annular extension 18. Lid 5 is provided with a groove 19, adapted to coöperate with 65 the extension 18 in supporting the cover on the flange, as shown in Fig. 2. A portion of the cover is extended over the reservoir 11 and moistening roll 4, and upon the underside of this portion of the cover a journal lug 20 is formed, which coöperates with journal lug 12 on the base, in rotatably supporting the moistening roll. A handle 21 is provided on the cover for removing it to 70 place new tape rolls in the receptacle, and 75 fresh water in the reservoir.

It will be noticed that the roll of tape rests upon the base, as shown in Fig. 2, and that consequently its frictional engagement therewith will prevent the roll unwinding 80 too far, and will maintain the tape in sufficiently taut engagement with the moistening roll when using the tape, to insure its proper and thorough moistening.

In using the machine, the tape is drawn 85 over the surface of the moistening roll, as indicated by the full line in Fig. 1, until a sufficient quantity has been moistened. It is then brought back over the knife edge 16, as shown by dotted line in Fig. 1, and 90 severed.

The knife edge 16 is extended in relation to the moistening roll, so that the amount of tape left projecting beyond it, after cutting off the length desired, not only extends across the opening between the moistening roll and the portion 15 of the flange, but it also extends beyond the moistening roll sufficiently to insure this portion of the tape becoming dry enough before each subsequent using thereof, to enable one to handle it without causing his fingers to become sticky.

Having thus described my invention, what I claim is:

1. A tape moistener comprising a base having a tape roll receptacle and a reservoir formed therein, a journal lug located in the reservoir, a centering lug located in the receptacle, a moistening roll journaled 110 on the journal lug and a cover located on the receptacle and having a journal lug on

its underside adapted to coöperate with the journal lug in the reservoir in supporting the moistening roll.

2. In combination in a tape moistener, a
5 base provided with a neck portion, said neck portion having a reservoir formed therein and a flange formed on the base, extending from one side of the neck portion around the base to the opposite side of the neck
10 portion and forming a tape roll receptacle in the base, a lid adapted to cover the re-

ceptacle and the reservoir, and a moistening roll mounted in the reservoir and located adjacent to one side of the neck portion.

In testimony whereof, I have hereunto 15
subscribed my name this 8th day of August,
1913.

SAMUEL G. STUCKEY.
